[57] CLAIM

The ornamental design for a roll products dispenser casing, as shown and described.

DESCRIPTION

FIG. 1 is a top, front, and right side perspective view of a roll products dispenser casing showing our new design;

FIG. 2 is a front elevational view thereof;

FIG. 3 is a left side elevational view thereof, the right side being a mirror image of that shown;

FIG. 4 is a top plan view thereof;

FIG. 5 is a bottom plan view thereof;

FIG. 6 is a top, front, and right side perspective view of an alternate embodiment thereof;

FIG. 7 is a front elevational view of the embodiment of FIG. 6;

FIG. 8 is a left side elevational view of the embodiment of FIG. 6, the right side being a mirror image of that shown;

FIG. 9 is a top plan view of the embodiment of FIG. 6; and

FIG. 10 is a bottom plan view of the embodiment of FIG. 6.

The rear of both embodiments is plain and unornamented and the broken-line portions of the dispenser are for illustrative purposes only and form no part of the claimed design.
